[57] CLAIM

The ornamental design for an angled connector, as shown and described.

DESCRIPTION

FIG. 1 is a top plan view of an angled connector showing a first embodiment of our new design;

FIG. 2 is a front elevational view thereof;

FIG. 3 is a bottom plan view thereof;

FIG. 4 is a rear elevational view thereof;

FIG. 5 is an elevational view of the left side of the connector illustrated in FIG. 1;

FIG. 6 is an elevational view of the right side of the connector illustrated in FIG. 1;

FIG. 7 is a top plan view of an angled connector showing a second embodiment of our new design;

FIG. 8 is a front elevational view thereof;

FIG. 9 is a bottom plan view thereof;

FIG. 10 is a rear elevational view thereof;

FIG. 11 is an elevational view of the left side of the connector illustrated in FIG. 7; and,

FIG. 12 is an elevational view of the right side of the connector illustrated in FIG. 7.
